A. J. HANGLIN

LEATHER DEGREASING PROCESS

Original Filed Dec. 6, 1919

Patented Oct. 13, 1925.

1,556,598

UNITED STATES PATENT OFFICE.

ALBERT J. HANLIN, OF NEWARK, NEW JERSEY.

LEATHER-DEGREASING PROCESS.

Application filed December 6, 1919, Serial No. 343,065. Renewed March 5, 1925.

To all whom it may concern:

Be it known that I, ALBERT J. HANLIN, a citizen of the United States, residing at Newark, New Jersey, have invented certain new and useful Improvements in Leather-Degreasing Processes, of which the following is a clear, full, and exact description.

This invention relates to the degreasing of materials such as the skins and hides of animals and fish, and particularly to the degreasing of such materials when in their raw, wet condition before being subjected to the liming or tanning processes, and the invention has for its general object an improved process for effecting the degreasing of the aforementioned and other materials and for conserving and recovering the solvent employed and the grease removed.

Heretofore it has been customary to effect the degreasing of skins to be tanned after the liming operation, and so far as I am aware, no successful process or means has ever before been devised for degreasing skins or hides in their raw wet condition, that is, as they are taken from the animal or fish, and also skins which have been salted, pickled, or otherwise treated by the packer, butcher, or other person who holds them in such a condition that putrefaction will not take place before the skins are treated by the tanner. The process is also applicable to dry hides or skins which have not been treated by the tanner.

In carrying out the novel degreasing process, I preferably employ apparatus such as that herein illustrated and which constitutes a part of the present invention, this apparatus being shown on the accompanying sheet of drawings in which

Fig. 1 is a side elevation of the essential parts of the apparatus for carrying out the process of this invention;

Fig. 2 is a longitudinal section through the rotatable drum, in which the main step of the degreasing process is effected; and

Fig. 3 is a transverse section through the drum shown in Fig. 2.

The apparatus illustrated comprises a rotatable drum 2 having hollow trunnions 4 and 6 mounted in bearings 8 and 10, the drum having a perforated false bottom 12 between which and the outer wall of the drum a steam pipe 14 is located, this pipe being connected through the hollow trunnion 4 by a connection 16, (allowing the pipe 14 to revolve with the drum), with a pipe 18

from any suitable source of steam supply which is controlled by a valve 20.

The drum 2 is provided with a door 22 through which the material to be degreased can be introduced into the drum, this door being constructed to seal the drum airtight, and the drum is also provided with a drainage cock 24 for the solvent and its contained grease and water, an air intake pet cock 26 and with a drainage cock 28 for the steam pipe 14. Within the drum are paddles or baffle plates 30 which serve to insure mixing of the material to be degreased with the solvent when the drum rotates. A driving pulley 32 connected to any suitable source of power may serve to effect the rotation of the drum.

Through the other hollow trunnion 6 of the drum, the interior of the drum is rotatably connected by a union 34 with a pipe 36, which in turn is connected by a double T-joint 38 with a pipe 40 leading to a condenser coil 42; with a second pipe 44 leading to a storage tank 46, and with a third pipe 48 leading to a still 50, the condenser coil 42 being also connected through a pipe 51 with the storage tank 46. By means of cocks 52, 54 and 56, the various operative connections between the pipe 36 and the other pipes hereinafter to be described may be effected.

The storage tank 46 is connected by a pipe 58 to a vacuum pump 60, which discharges through a pipe 62 into a discharge tank 64 containing any suitable material or chemical for recovering vapors which may pass through said pump 60. The storage tank 46 is surrounded by a water jacket 66 through which cold water may be caused to pass from any suitable source of supply connected to the pipe 68 and controlled by the cock 70, this water preferably then passing through a pipe 72 into the condenser tank 74 enclosing the condenser coil 42, and from the condenser tank through an outlet pipe 76 to the discharge.

The still 50 is surrounded by a steam jacket 78 connected by a pipe 80 to any suitable source of steam supply controlled by a valve 82 in said pipe, and this still is preferably provided with several pet cocks 84, 86 and 88 to permit the entrance of air, and with a drainage cock 90. A pipe 92 which may be connected to the drainage cock 24 of the drum 2 is arranged to conduct the solvent with its contained grease and water

into the still 50, this pipe being provided with a valve 94.

The storage tank 46 is preferably provided with a vacuum gage 96 and a vacuum relief pet cock 98, and the connection 51 between the condenser and the storage tank is preferably provided with a sight glass 100.

In carrying out the novel process of this invention with the novel apparatus just described, the hides or skins to be degreased are introduced into the drum 2, through the opening 23, normally closed by the door 22, together with the solvent, a suitable proportion, when naphtha is used as a solvent, being about 35 gallons of naphtha for each 100 pounds of wet hides or skins. In order to produce the internal pressure in the drum, which is one of the important novel features of the process of this invention, the naphtha is preferably introduced into the drum at a temperature below normal room temperature, say about 60° F., and the drum is then closed and sealed air-tight and is set in rotation. Heat is then applied through the steam pipe 14 until the temperature of the contents of the drum has been raised to approximately 80° F., thereby attaining an internal pressure of about 3 pounds, due to the expansion of the air and the naphtha.

The agitation of the contents of the drum, while subjected to this internal pressure, by the continued rotation of the drum, causes the naphtha to penetrate the hides or skins and partly to dissolve and partly to emulsify the grease and to displace some of the water in the hides or skins.

The drum is rotated for a suitable length of time, the length of time naturally varying with the size of the drum and with the amount and thickness of the material treated. I have found the time required to vary from 15 minutes to an hour, in accordance with the varying conditions just enumerated.

After the drum has been rotated a suitable length of time, it is stopped, the drain cock 24 is connected with the pipe 92, and the liquid is drawn off into the still 50, all valves in the drum being preferably opened to allow free ingress of air to facilitate the draining of the liquid. When the draining is completed, the drum is disconnected from the still, the drain cock 24 closed, the same quantity of fresh cold naphtha as used in the first instance is introduced into the drum, and the operation repeated. The liquid is then again drawn off into the still 50 through the drain cock 24 and pipe 92, and all valves again closed and, the vacuum pump 60 being in operation, the drum is revolved and the valve 52 on the pipe 36 leading to the vacuum pump through the pipe 40, condenser coil 42, pipe 51, storage tank 46 and pipe 58 is opened, the valves

56 and 54 being closed, and this connection is maintained until a maximum vacuum is attained in the drum, as shown by the vacuum gage 96. This vacuum is maintained for a short time, say about five minutes, and then the pet cock 26 is opened sufficiently to allow air to pass into the drum 2 in a volume so small that it will not overcome more than two or three inches of vacuum, the pump 60 being maintained in operation. The pump 60 is then continued in operation until all naphtha vapors are removed from the drum 2; this operation usually taking from 15 minutes to an hour, and the result may be observed in the sight glass 100. This completes the degreasing operation and the drum is opened and the contents are removed.

To recover the solvent from the still 50, the liquid and semi-solid material which has been drained from the drum 2 into the still are heated until most of the volatile solvent is driven off through the pipes 48, 40 and condenser pipe 42 into the storage tank 46, the still 50 being heated by the steam jacket 78. In order to recover still more of the solvent, the still is connected with the vacuum pump through the storage tank and condenser, the valves in the still are closed, and the pump is operated until a maximum vacuum is attained in the still. The pet cocks 84, 86 and 88 on the bottom of the still are then opened and air is admitted in volume sufficient to maintain within four or five inches of maximum vacuum while the pump is continued in operation, this operation being continued until all the solvent is removed. The still is preferably provided with a cup connection 102 to facilitate washing out of the still, this connection being normally closed by valve 104. The grease in the still may be drawn off through the drainage cock 90. Any vapors which pass through the vacuum pump 60 may be recovered in the discharge tank 64 by providing suitable chemicals or other means for effecting combination or condensation.

From the foregoing description of the novel degreasing process and the apparatus for practicing this process, some of the advantages of the process will be apparent. By treating raw, wet hides and skins under pressure accompanied by agitation, I secure a practically complete removal of grease, something that has not heretofore been done with wet material, such as pigskins, sheepskins, goatskins, dogskins, seal and porpoise skins, and the other raw skins used in the tanning industry.

The advantage of removing the grease before the tanning operation is begun will be obvious to those skilled in the art, such removal serving to effect a shortening of the time required for liming in the beamhouse

because of the fact that the materials used can more rapidly attack the hair cells of the degreased hide and thus permit the removal of the hair or wool in a shorter time. This is important since it lessens the harmful effect of caustic lime and sodium sulphide on the raw hides or skins, resulting therefore in the production of a finer and stronger leather in a shorter time than by processes heretofore practiced. The process also is more economical of solvent than processes heretofore used, and a greater percentage of grease is recovered in a useful form.

Up to the present time most sheepskins and many other kinds of skins have been only partially degreased before tanning. What grease has been left in the skins, if it interferes with the proper finishing of the leather, is removed after the tanning process, being usually removed from the dry tanned leather. This practice results also in the removal of the grease and oils which the tanner has used in his processes. Moreover, as naphtha does not dissolve alkalis, these if used in conjunction with oils or soap in the stuffing or fat liquorizing treatment of the leather are left in the leather and subsequently act upon the leather fibre and weaken it.

When my process is employed, the degreasing of the tanned leather is not necessary, and therefore the greases and oils used in stuffing are not removed, the quality of the resultant leather is therefore better, and the danger of injury to the leather by the excessive heat sometimes employed with processes now in use is avoided.

It will be understood that the process may be practiced with any suitable grease sol-

vent, such as naphtha, carbon tetra-chloride, carbon bisulphide, tetra-chlor-ethylene, these solvents being capable of dissolving animal and fish oils and grease and emulsifying them under the conditions produced with the apparatus herein described.

To facilitate continuous operation, it will be understood that a battery of degreasing drums may be associated with a single pump, still, condenser and storage tank, such an obvious modification of the structure herein shown not requiring special illustration.

Although the invention is particularly described in connection with the degreasing of raw wet skins or hides of animals and fish, it is obvious that the process may be utilized in degreasing other materials, such, for example, as wool.

What I claim as new is:

That improvement in the art of degreasing raw wet skins or hides of animals and fish, which consists in enclosing the material to be degreased and a readily volatilizable grease solvent in a drum, sealing the drum air tight, raising the temperature of the drum contents to a degree to insure the production of substantial pressure in the drum, the initial temperature of the drum contents being such that the temperature required to produce such pressure will not be so high as to injure the skins or hides, then agitating the drum contents, while maintaining the internal pressure, to effect a solution or emulsion of the grease, and then removing the solvent with its contained grease and water.

Signed at Newark, New Jersey, this 2nd day of December, 1919.

ALBERT J. HANGLIN.
